UNITED STATES PATENT OFFICE.

ELMER LOVELL SMITH, ARTHUR E. PHELON, AND PAUL LANGHAMMER, OF SPRINGFIELD, MASSACHUSETTS, ASSIGNORS TO PACKAGE MACHINERY COMPANY, OF SPRINGFIELD, MASSACHUSETTS, A CORPORATION OF MASSACHUSETTS.

WRAPPING MACHINE FOR STICK CANDY.

Original application filed September 4, 1923, Serial No. 660,798. Divided and this application filed February 13, 1926. Serial No. 88,021.

This invention relates to an improvement in stick candy wrapping machines and has for its object the provision of a machine having an improved hopper and feeding means.

5 This application is a division of our Patent No. 1,597,932, granted August 31, 1926.

Hard candy in round stick form presents many difficulties in the way of wrapping the same by mechanical means, due to the fragile 10 nature of the candy, and also to irregularity in size and shape of said sticks, even when of the same price grade. The present improvement aims to provide a machine for feeding sticks of such various sizes and shapes as 15 would likely be encountered within the same general price grade, and to handle such sticks in a manner sufficiently gentle to prevent breakage thereof.

More particularly, the present invention 20 is an improvement upon the stick candy wrapping machine described and shown in the patent to Elmer L. Smith and Arthur E. Phelon, No. 1,597,931, granted August 31, 1926. In a general way, the operation of the 25 present machine is similar to the machine of said Patent No. 1,597,931, and may be briefly outlined as follows. The candy sticks, usually of round cylindrical form, are contained in a hopper which is provided with suitable 30 agitating means, not herein shown, for causing the sticks to be directed continuously into a downwardly directed spout. Suitable escapement devices are provided to release one stick at a time from the outlet of said spout. 35 A feed pusher engages each stick after it issues from said spout outlet to advance the same against a wrapper and to advance said stick and wrapper into a tucking channel so as to partially wrap the wrapper around the 40 stick. Tucking mechanism may be arranged to then start the wrapper for a rolling operation around the stick, which rolling operation is effected by suitable rolling means into which the stick and wrapper are subsequently 45 advanced. During the rolling operation, portions of the wrapper which extend beyond each end of the stick are engaged by end twistlers for twisting the same and thus securing the wrapper permanently around the stick. From the rolling means, the 50

wrapped sticks are delivered to a suitable discharge chute or platform.

Referring to the drawings which show the preferred embodiment of the invention:

Fig. 1 is a side elevation of the machine 55 omitting such features as will be understood from reference to said Patent No. 1,597,931, above mentioned; and

Fig. 2 is a detail section through the feed 60 spout extending from the hopper.

Referring more particularly to the drawings, the main frame of the machine indicated at 1 has suitably mounted thereon various drive shafts and cam shafts for operating the parts of the machine as disclosed in said prior case above referred to, it being thought unnecessary to disclose said driving parts in any greater detail in the present case than herein shown.

Referring to Fig. 1, the rear or delivery 70 end of the hopper is indicated at 2, it being understood that said hopper is designed to contain a plurality of sticks to be wrapped and to feed the same continually to a downwardly directed spout 3. Below the outlet of 75 said spout is mounted a receiver 4, pivoted at 5 on the main frame, and having a spring 6 connected to one end thereof to normally hold the receiving end of the same upwardly in yielding position toward said spout outlet. An adjustable stop pin 6' limits the action of said spring 6. Mounted for sliding movement past the outlet of said spout 3 is a feed pusher 7 carried on rod 8, which is 80 slidably supported in brackets such as 16 fixed on said main frame. The means for reciprocating the rod 8 are not described, but may be of any suitable character such as shown in said prior patent referred to.

Upon the bracket 9 forming the forward 90 wall of said spout 3, is a rocking shaft 10 carrying a stop member 11 having a lower hook portion 12 extending through an opening 11' in said spout wall into the spout passageway, for the purpose of engaging sticks 95 and controlling the passage thereof through said passageway, as hereinafter described. Fixed upon the shaft 10 is an operating lever 13 adapted to be actuated by an outwardly extending lug 14 on said feed pusher 7 when 100

the feed pusher is in its advanced position, and preferably near the end of its forward stroke. A spring 15 also connects said lever 13 with said main frame to normally hold the stop lever 11 in the position shown in Fig. 2, whereby it engages a stick in said spout and stops the flow of sticks to the receiver 4.

The pusher 7 carries on its upper surface a soft resilient pad of rubber or the like 17, which pad lies directly beneath the spout outlet when said pusher is at the forward end of its stroke. Just previous to reaching the end of said forward stroke, the lug 14 carried on said pusher 7 engages lever 13 to release a stick from said spout and allow the same to drop onto said pad 17. Upon the backward movement of said pusher 7, stop member 11 is returned by its spring 15 into engagement with the following stick in said spout, as shown in Fig. 2, and the previously released stick S is dropped from the upper surface of said feed pusher 7 upon the yieldingly mounted receiver 4.

The feed pusher 7 is designed to thrust the sticks one at a time with a wrapper in advance thereof into a tucking channel, which may be formed with a bottom 18 and top 38. The tucking channel may be arranged in a convexly curved path as shown to lead tangentially into a concavely curved wrapping bed, more fully described in the prior Patent No. 1,597,931, referred to.

The yielding receiver 4 is preferably connected, as shown, by link 41 to an actuating lever 28, said link 41 having free sliding movement in a downward direction through said actuating lever. Stop nuts 41' on said link 41 limit the upward sliding movement thereof through said lever 28. The actuating lever 28 is pivoted at 42 upon the main frame and carries at its rear end a roll 43 actuated by cam 44 rotatable on a shaft 45 mounted in the main frame. The cam 44 and actuating lever 28 are designed to periodically and temporarily pull down the forward part of receiver 4 and the rear end of said channel bottom 18. This lowering of said receiver and channel bottom is arranged to take place at the time the feed pusher 7 begins the advance of a stick with a wrapper into said tucking channel and the purpose thereof is to relieve the stick of the necessity of forcing its way between the receiver 4 and fixed lip 46 of said outlet passage and between the bars at the mouth of said tucking channel, which might be the cause of breakage of said sticks. A spring 47 connecting the lever 28 to the main frame tends to keep the cam roll of said lever in engagement with the cam 44 and a stop 48 on the main frame is also provided to limit the upward movement of the forward end of said lever 28.

While we have shown and described with some particularity our improvement in an

embodiment at present preferred by us, it is to be understood that various changes in detail of design and arrangement of parts may readily be made without departing from the substance and scope of the invention as hereinafter claimed.

Claims:

1. In a machine of the class described comprising in combination, a downwardly directed spout for delivering sticks of candy of different sizes, a receiver therebelow for receiving said sticks, means acting in said spout to release single sticks from said spout, and a pusher for removing sticks on said receiver operable to actuate said means, the said receiver being movable and arranged to be depressed by a stick as it is moved thereover by the pusher.

2. In a machine of the class described, in combination, a downwardly directed spout for delivering sticks of candy, a movable receiver therebelow, an escapement device in said spout for delivering sticks one at a time therefrom, a pusher reciprocable across said receiver adapted to operate said escapement in its forward movements, and means for moving said receiver away from said spout as the pusher moves therewith.

3. In a machine of the class described, in combination, a spout for delivering sticks of candy, an escapement device in said spout for releasing one stick at a time from said spout, a movable receiver below said spout for receiving released sticks, a feed member movable back and forth between said spout and receiver for removing sticks on said receiver, the said escapement and feed member being arranged so that a stick is released onto said member during a rearward movement thereof.

4. In a machine of the class described, a spout for delivering sticks of candy, a pusher reciprocable back and forth beneath said spout, an escapement member in said spout operable by said pusher to release a single stick onto said pusher, a side wall of said spout disposed adjacent said pusher to prevent said stick being carried rearwardly thereby so that as the end of the pusher travels past said wall the stick will fall onto the receiver to lie in front of the pusher.

5. In a machine of the class described, a spout for delivering sticks of candy, a pusher reciprocable back and forth beneath said spout, an escapement member in said spout operable by said pusher to release a single stick onto said pusher, a side wall of said spout disposed adjacent said pusher to prevent said sticks being carried rearwardly thereby so that as the end of the pusher travels past said wall the stick will fall onto the receiver to lie in front of the pusher, and a resilient pad on the upper side of said pusher for receiving sticks delivered thereto.

6. In a machine of the class described, a spout for delivering sticks of candy, a pusher

reciprocable beneath said spout, an escape-
ment for delivering sticks one at a time onto
said pusher, a receiver underlying said
spout, means for transferring a stick from
said pusher to said receiver as the pusher
moves to its rearward position, a channel
adjacent said receiver all adapted and ar-
ranged whereby a stick is transferred from

the receiver to the channel as the pusher
moves forwardly from its rearward position. ¹⁰

In testimony whereof we have affixed our
signatures.
